UNITED STATES PATENT OFFICE.

ELISHA PECHEY, OF LONDON, ASSIGNOR TO STEPHENSON, BLAKE & CO., OF SHEFFIELD, ENGLAND.

DESIGN FOR A FONT OF TYPE ORNAMENTS.

SPECIFICATION forming part of Design No. 21,176, dated November 17, 1891.

Application filed September 1, 1891. Serial No. 404,466. Term of patent 3½ years. Registered in England March 29, 1890, No. 146,843.

To all whom it may concern:

Be it known that I, ELISHA PECHEY, a subject of Her Majesty the Queen of Great Britain, residing at London, England, have invented and produced a new and original Design for a Font of Type Ornaments, of which the following is a specification, reference being had to the accompanying drawings, forming part thereof.

10 This design has been registered in Great Britain under date of March 29, 1890, No. 146,843.

15 The font of type ornament consists of thirteen pieces, which are represented in the drawings as Figures 1 to 13, inclusive. The general idea of the ornamentation is that of curved or waved conventional tendril-like figures.

20 It will be seen that Figs. 1, 2, 3, 6, and 7 are left-handed duplicates of Figs. 13, 12, 11, 9, and 8, respectively, while Figs. 4, 5, and 10

are single figures, which may be used for center pieces and the like. These figures when fitted together or combined and repeated may be employed to form various ornamental patterns, which may be used as borderings or 25 ornamentations for or be intermixed with letter-press matter, the general idea of one form of pattern which may be produced therefrom being that of a trailing vine-like figure.

What I claim is—

30 The design for a font of type ornaments, as herein shown and described.

In testimony whereof I have hereunto set my hand in the presence of two subscribing witnesses.

E. PECHEY.
